W. AGER.
HULLING AND CLEANING RICE.

No. 18,177.

Patented Sept. 15, 1857.

UNITED STATES PATENT OFFICE.

WILSON AGER, OF RHORSBURG, PENNSYLVANIA.

MACHINE FOR CLEANING RICE.

Specification forming part of Letters Patent No. 18,177, dated September 15, 1857; Reissued October 10, 1871, No. 4,579.

To all whom it may concern.

Be it known that I, WILSON AGER, of Rhorsburg, in the county of Columbia and State of Pennsylvania, have invented a new 5 and useful Improvement in Hulling and Cleaning Rice; and I do hereby declare that the following is a full, clear, and exact description of the same, reference being had to the annexed drawing, forming part of 10 this specification, in which—

Figure 1 is a top view of the machine by which the operation is effected. Fig. 2 is a vertical section on line $x-x$. Fig. 3 is an elevation of driving wheel end of machine. 15 Fig. 4 is an elevation of the opposite end showing pinions for rotating the bur. Fig. 5 is a view of the bur, removed from the shell. Fig. 6 is a view showing interior of shell.

20 Similar characters of reference in the several figures denote the same part.

The object of my invention is the cleaning of the grain ready for use after the removal of the husk therefrom. Before describing 25 the means I employ to effect that end I will refer briefly to the structure of the grain to be operated upon.

The husk of the paddy is attached to the grain at one extremity only, and can readily 30 be separated therefrom by pressure in direction of the length of grain. In fact this is the easiest way to effect the separation. After the removal of the husk the grain is found to be covered with a coating which 35 can readily be removed by rubbing upon some rough substance. The removal of this coating and the separation of the germ constitute the cleaning of the grain. Regarding the husk, it will be found that its 40 outer surface is roughened somewhat like a file; which property I avail myself of in the cleaning process as will be hereinafter set forth.

The nature of my invention consists in 45 utilizing the husk of rice as a cleaner of that grain by subjecting the mixture of grain and husk resulting from the hulling process, to a packing and rubbing operation whereby the file like coating of the husk 50 is rendered available for the desired purpose. The manner in which I perform this packing and rubbing operation consists in the passing of the rice and husk between a shell and bur rotating in opposite directions and so dressed that the husk shall act

upon and remove the inner coating aforesaid; and the germ be also separated from the grain during the cleaning operation.

The details of construction and operation being as hereinafter set forth. 60

In the drawing S is the shell supported by hollow shafts $a a'$ in bearings $b b'$, and rotated in direction of arrow 1, by power applied to wheel A, secured on hollow shaft a' . 65

B, is the bur having spindles $c c'$ at its extremities passing through hollow shafts $a a'$, and rotated in direction of arrow 2 (Fig. 4), by reason of cogwheel connection $d d'$ between shafts a' and f ; and pinion connection $e e' e''$ between shaft f and spindle c . The hollow shafts $a a'$ are upon heads $g g'$, secured in the ends of the concave S, as shown in Fig. 2. 70

The shell S is incased in bands $h h'$ at its extremities as shown in Figs. 1 and 2. On band h' is the feed hopper i , communicating with the surface of the bur by openings i' in the shell (Figs. 2 and 6). Band h has a discharge pipe k ; outlets k' in the shell permitting the passage of the grain. The bands are secured to the supports D D' by screws s , and the shell rotates freely within them. 75

The bur B is formed with a spiral flange l occupying the portion beneath the band h' , 80 for conveying the paddy to the hulling portion of the machine. This hulling portion is cylindrical and is represented in Fig. 5 by the part of the bur between y and z . Its surface has a dress consisting of a system of indentations n , having their greatest depth at the base and reaching the surface at the point. The hulling portion of the shell shown between y' and z' , Fig. 6, has the same dress arranged in inverse order. This dress is 85 shown at X and X', where X represents a portion of the hulling shell of full size, and X' a portion of shell and bur of full size, revolving in opposite directions as indicated by the arrows 3 and 4, and showing the reverse position of the indentations. 90

Upon the hulling cylinder is the double series of deflecting blocks m , arranged spirally, as shown in Fig. 5, the action of which will be hereinafter set forth. 95

From z to z'' of the bur B is a spiral flange o which conveys the grain and husk to the cleaning portion of the machine. The bur and concave of this part has the cross section shown at Y, and the dress shown at Y'; 100 110

the cavities p being so arranged on the shell and bur as that the two series shall cross when the parts are in position. The cavities shown at Y' are of full size.

- 5 The operation of hulling and cleaning is as follows: The paddy is fed by hopper i as shell and bur are rotated in the opposite directions indicated by arrows 1 and 2. On passing through the openings i' of the shell 10 the rice encounters the spiral flange l and is conveyed by it to the space between the hulling portions of shell and bur. The paddy on entering this space will encounter some one of the deflecting blocks m which will turn 15 the grain across the axis of the bur, and in so doing cause one end of the grain to enter a cavity n in the shell as the other is caught by one of the cavities n in the bur, as shown at X' . The rotation of shell and bur as 20 shown by arrows causes a pressure in direction of the length of the grain, effecting the separation of the husk as before stated. The grain and husk then pass onward to the spiral flange o , which conveys them to the 25 cleaner. There the rice and husk pack together as the shell and bur rotate in opposite directions shown by arrows at Y ; the rough surface of the husk rubbing upon the grain and acting as a file to remove the coating therefrom. The eccentricity of the operating surfaces of this portion of the machine cause the greatest packing when the ridges r are opposite each other. And when 30 the ridges pass to the position shown at Y ,

the increase of space causes the mixture of 35 grain and husk to be changed in relative position, whereby other portions of the grain are submitted to the action of the husk. Therefore since the shell and bur rotate with considerable rapidity there is a continual 40 change of position of the substance passing between them, causing the grain to be thoroughly operated upon, and the coating entirely removed during the transit of the mixture from z'' to z''' . The cleaned rice and 45 husk are then forced out through passage k' , after which the husk may be separated from the grain in any suitable manner.

During the rubbing of rice and husk the end of the grain will be brought in contact 50 with the edge of some one of the cavities p , which will cause the germ to separate from the grain.

Without claiming the mere utilizing of the rice husk, what I claim as new and of 55 my own invention and desire to secure by Letters Patent, is—

The method of cleaning rice by submitting the mixture of grain and husk resulting from the hulling process, to an alternate 60 packing and loosening action produced by surfaces dressed and operating substantially as hereinbefore set forth.

WILSON AGER.
